C. D. BURNEY,
TOWING ANCHORAGE FOR TOWED BODIES.
APPLICATION FILED JULY 22, 1919.

Patented Oct. 21, 1919.

UNITED STATES PATENT OFFICE.

CHARLES DENNISTON BURNEY, OF KILMESTON, ALRESFORD, ENGLAND.

TOWING-ANCHORAGE FOR TOWED BODIES.

1,319,565.

Specification of Letters Patent. Patented Oct. 21, 1919.

Original application filed September 18, 1917, Serial No. 192,019. Divided and this application filed July 22, 1919. Serial No. 312,591.

To all whom it may concern:

Be it known that I, CHARLES DENNISTON BURNEY, a subject of the King of Great Britain, residing at Dean Holme, Kilmeston, 5 Alresford, in the county of Hants, England, have invented certain new and useful Improvements in Towing-Anchorage for Towed Bodies, of which the following is a specification.

- 10 This invention relates to means for attaching a towing cable to the head of a towed body intended to be towed from a ship, more especially a body provided with an explosive charge by which a submarine vessel or other body may be destroyed. The 15 towing cable may be an electrical one and serve to convey current for actuating the firing mechanism, but this forms no part of the present invention. The towed body 20 may be of the kind described in the specification of my application No. 192019, from which the present application is divided, and now known under the name of a "paravane."
- 25 The chief object of the present invention is to provide a secure anchorage for the towing cable, which anchorage permits of relative rotation of the towing cable and towed body or paravane without slackening.
- 30 In order that the said invention may be clearly understood and readily carried into effect, the same will now be described more fully with reference to the accompanying drawings, in which:—

35 Figure 1 is a section of the head of a towed body or paravane showing in section the anchorage for the towing cable; and

Fig. 2 shows a modification.

The paravane forms no part of the present 40 invention and only a small portion of it is shown in Fig. 1, including the head 1, with a depressing plane 2 which causes the paravane to be deflected downwardly and outwardly in known manner when it is towed 45 through the water, and with striker mechanism 3.

The towing cable 68, which is an armored 50 electric cable, is connected to the anchorage 69 in the head of the paravane. This consists of a plug 70 internally threaded and with an aperture in the lower face through which the inner core of the cable passes. A sleeve 71 is mounted on the armored part of the cable and carries an inner sleeve 72 55 adapted to rotate within the outer sleeve 71.

The armoring of the cable is anchored in the following manner. Rubber buffers 73, a washer plate 74, a splicing bush 75 and a splicing ring 76 are fitted over the armoring, the splicing ring having a head or flange 77, 60 formed with holes 78, through which the strands of the armoring are passed. The strands are then bent back as at 79 against the outside of the ring. The bush 75 and ring 76 are formed with divergent and convergent adjacent surfaces.

On the required parts being assembled on the towing cable, the outer sleeve 71 is screwed into the plug 70 and when fully home all the parts are locked together, the 70 adjacent surfaces of the bush and ring securely clamping the strands of the armoring. The head of the outer sleeve is preferably made of polygonal shape to receive a lock nut 80 adapted to fit over the head of the sleeve and to be retained in place by an eye bolt 81 screwed into the plug 70. When this has been done, the rotation of the outer sleeve 71 is prevented, while rotation 75 of the inner sleeve is still possible, the rubber buffers preventing vibration and chafing of the cable within the sleeve. This form of anchorage enables the towing cable and paravane to rotate relatively to each other 80 and at the same time prevents any slackening 85 back of the outer sleeve.

In the modification shown in Fig. 2, the cable 68^a is not an electrical one and is connected to the towed body through a cutter comprising jaws 118, 119 and mounted 90 on the nose 1 of the towed body for the purpose of cutting the mooring rope of a mine. The modified tow anchorage 123 consists of a stream line sleeve 124 having a central bore, provided with rubber buffers 125, 95 and a cup 126, coned internally. The strands of the towing cable 68^a are opened out and then bent back on themselves. If desired the inner strands may be removed 100 for any desired distance. The coned cup is then pushed up until all the wires are inside and the interior filled with liquid metal such as white metal. Resin is preferably added to the cup, to prevent sticking of the white metal to the same so that the cone 105 shaped pudding 127 on the end of the cable is free to rotate in the cup.

The sleeve 124 is screwed on to a plug 128 which is secured by a bolt 129 to a shackle 130 which in turn is secured by a 110

bolt 131 to the eye plate 122, the two bolts being arranged at right angles so as to permit of universal movement between the tow anchorage and the cutter block of the para-vane. The end of the sleeve 124 remote from the anchorage is cut at an incline to permit the mine mooring passing readily from the towing cable to the anchorage without encountering any obstructions, the other end of the anchorage being arranged and constructed to prevent any obstruction arising to the passage of the mooring of the mine along the anchorage into the cutter jaws.

15 What I claim and desire to secure by Letters Patent of the United States is:—

1. A towing anchorage for a cable attached to a towed body, comprising a member secured to the towed body, through which member the end of the cable is passed, a coned sleeve, means for gripping the strands of the cable against the said sleeve on opening out and bending back the said strands, and a resilient buffer.

20 2. In a towed body provided with an ex-

plosive charge and towed by an armored electric cable, a tow anchorage for the said cable, comprising a member secured to the towed body and provided with an aperture through which the conducting cable core can 30 pass, an outer sleeve secured to the said member, a rotatable inner sleeve, a resilient buffer and securing means engaging and gripping the strands of the cable armoring.

3. In a towed body provided with an explosive charge and towed by an armored electric cable, a tow anchorage for the said cable, comprising a member secured to the towed body and provided with an aperture through which the conducting cable core 35 can pass, an outer sleeve secured to the said member, a rotatable inner sleeve, a resilient buffer, a splicing bush and a splicing ring having divergent and convergent adjacent surfaces, the splicing ring being 40 provided with holes through which the strands of the armoring are passed and bent back.

CHARLES DENNISTON BURNEY.
